F. ROESE.
DUST RECEIVER FOR GRINDING AND POLISHING MACHINES.
APPLICATION FILED OCT. 16, 1916.

1,255,230.

Patented Feb. 5, 1918.

UNITED STATES PATENT OFFICE.

FRED ROESE, OF PENN YAN, NEW YORK.

DUST-RECEIVER FOR GRINDING AND POLISHING MACHINES.

1,255,230.

Specification of Letters Patent.

Patented Feb. 5, 1918.

Application filed October 16, 1916. Serial No. 125,875.

To all whom it may concern:

Be it known that I, FRED ROESE, a citizen of the United States of America, and resident of Penn Yan, in the county of Yates, 5 in the State of New York, have invented new and useful Improvements in Dust- Receivers for Grinding and Polishing Machines, of which the following, taken in connection with the accompanying drawings, is 10 a full, clear, and exact description.

This invention relates to certain improvements in dust receivers for grinding and polishing machines adapted to be used more particularly in connection with small polishing 15 or buffing wheels commonly employed by jewelers, opticians and other craftsmen, and has for its object the removal and collection of dust and the fine particles of precious metals which have considerable value.

20 In other words, I have not only sought to remove the objectionable rouge dust which is more or less poisonous to the operator, but also to recover the small particles of gold and silver commonly thrown off by 25 the polishing or buffing wheel, and usually very difficult to recover unless some special provision is made to accomplish this result.

Other objects and uses relating to specific 30 parts of the device will be brought out in the following description.

In the drawings—

Figure 1 is a front elevation of a polishing device and my improved dust collector in operative relation thereto.

35 Fig. 2 is an enlarged longitudinal vertical sectional view of the detached dust-collecting device shown in Fig. 1.

Fig. 3 is a transverse vertical sectional view taken in the plane of line 3—3, Fig. 2.

40 Fig. 4 is a perspective view of the removable tray in the head of the dust collector.

Fig. 5 is an enlarged transverse sectional view through the dust-collecting conduit taken on line 5—5, Fig. 1.

45 This dust collector is adapted to be used in connection with a rotary polishing or buffing wheel —a— and comprises a substantially rectangular sheet metal housing or dust-receiving case —1— having an inlet opening —2— in its front side and an outlet —3— in one end, the outlet being surrounded by a laterally projecting tubular fan case —4— in which is located a rotary fan or blower —4'—.

55 A tubular extension or dust-collecting

tube —5— is fitted at one end upon the outer end of the fan case —3— and extends downwardly therefrom, the lower end being disposed vertically and open at the bottom to allow the escape of the circulating air. 60

Within the upright lower end of the conduit —5— is located a plurality of, in this instance two, partitions or baffle plates —6— and —7— inclining upwardly and inwardly from opposite sides of the conduit to form 65 dust-collecting pockets —6'— and —7'—.

The partition —6— extends upwardly from a plane below and some distance above that of the upper end of the partition —7— and in spaced relation thereto so as to afford 70 a free passage for the escaping air between the partitions which are, therefore, disposed in intersecting planes at an angle to the axis of the extension —5—.

That is, the partition —6— extends from 75 one side upwardly and inwardly in an inclined plane and terminates at its upper end some distance from the opposite side of said extension beyond the vertical plane of the upper edge of the partition —7— which 80 terminates some distance from the partition —6— to form the intervening air passage previously mentioned.

The object in arranging the partitions in the manner described is to cause the heavier 85 particles of dust, such as gold, silver and other more or less valuable dust, to be collected in the pockets —7'— and —6'—, while at the same time permitting the escape of the circulating air. 90

The front inlet side of the housing —1— is preferably funnel-shape to facilitate the entrance of the dust-laden air which is drawn into the housing by the rotation of the fan or blower —4'— at substantially 95 right angles to the axis of the exit opening —3—, thus producing more or less eddying currents in the rear of the housing to allow the precipitation of the heavier particles of dust into the bottom thereof where it is collected within a removable tray —8—. 100

This tray is slidable along and upon the bottom of and within the housing —1— through the inlet opening in the front side thereof and may be removed by hand when 105 necessary to recover the more valuable portions of the dust collected therein.

The side of the tray adjacent the outlet —3— is provided with a lengthwise flange —9— projecting from the upper edge there- 110

of some distance above the bottom of the tray so as to overhang the adjacent portion of said bottom, thus producing an intervening dead air chamber to facilitate the collection of the heavier particles of dust before passing out through the outlet —3—.

The polishing or buffing wheel —a— is preferably located in the mouth of the inlet —2— of the housing —1— just above the bottom of the tray —8— so that the heavier particles of dust, resulting from the polishing or buffing operation, are precipitated directly upon the tray, while the lighter particles are carried with the current of air through the outlet and are collected in the pockets —6'— and —7'— and it, therefore, follows that the air which escapes from the discharge end of the conduit —5— is practically free from dust.

20 The polishing wheel —a— is shown as secured to an armature shaft —b— of an electric motor —B— which, together with the housing —1—, are mounted upon a suitable supporting bed or table —C— so that the axis of the shaft —b— and wheel —a— is substantially parallel with that of the outlet —3—, or at right angles to the inlet opening —2—.

25 The fan or blower —4'— is secured to a suitable shaft —10— which is coaxial with and extends through the outlet —3— and is journaled in bearings —11— on the outer end of the housing —1— and inner end of the blower case —4—.

30 The outer end of the shaft —10— is provided with a pulley —12— which is connected by a belt —13— to a pulley —14— on the armature shaft —b— so that the buffer wheel and fan may be driven by the same

35 source of power as the motor —B—. It is evident, however, that the fan may be driven from any available source of power if desired.

40 During the polishing or buffing operation, the heavier particles of dust thrown off by the wheel —a— are precipitated directly into the tray —8—, the flange —9— serving to hold back the particles which may lodge on the bottom of the tray against moving air currents produced by the fan —4'—, while at the same time the suction produced by the fan may remove the lighter particles of dust from the tray and cause them to be carried with the moving current of air into the extension —5— where the partitions —6— and —7— serve to trap any of the heavier or more valuable dust into the pockets —6— and —7'—, while the air which is free from

the dust is allowed to escape through the passage formed between the partitions.

When it is desired to recover this collected dust, the tray —8— may be removed in the manner previously described, and its contents emptied into a suitable receptacle.

In like manner, the extension —5— which is telescopically fitted upon the outer end of the fan case —4— may also be removed and inverted to deposit the contents of the pockets —6'— and —7'— into the same receptacle from which the more valuable dust may be separated from the valueless particles by any suitable method of separation, not necessary to herein illustrate or describe.

It is now apparent from the foregoing description that the purpose of the device is two-fold.

First,—to remove the dust produced by the polishing wheel from the atmosphere, and thereby avoid its inhalation by the operation, and

Second,—to recover the valuable particles, such as gold and silver,—which may be removed from the article operated upon.

What I claim is:

1. The combination with a rotary abrasive element, a dust-receiving case having an open side adjacent the abrasive element, a tubular fan case communicating with the dust-receiving case, a rotary fan in the fan case, an upright dust-collecting tube connected to the delivery end of the fan case and provided with interior pockets opening toward the fan case, and a tray slidable into and out of the dust-receiving case and provided with an overhanging inturned flange at the side adjacent the fan case.

2. The combination with a rotary abrasive element, a dust-receiving case having an open side adjacent the abrasive element, a fan case connected to the receiving case above the bottom thereof, a rotary fan in the fan case, and a dust-collecting tube having one end connected to the delivery end of the fan case and its other end extended downwardly and provided with partitions inclining inwardly and upwardly from the walls thereof to form interior pockets opening toward said delivery end of the fan case for collecting the dust and retaining it when the fan is at rest.

In witness whereof I have hereunto set my hand this 13 day of October, 1916.

FRED ROESE.

Witnesses:

JAS. C. GOODSPEED,
R. K. BASSAGE.
